UNITED STATES PATENT OFFICE

SAMUEL A. HARTMANN, OF JACKSON, MISSOURI

DRAINAGE SYSTEM

Application filed January 7, 1930. Serial No. 419,090.

This invention appertains to new and useful improvements for drainage systems for buildings, and the same has as its principal object, provision whereby circulating waters 5 may be trapped beneath a building and drained off to a sewer or some other remote point.

Another important object of the invention is to provide a drainage system which after 10 being installed will not require further attention.

Another important object of the invention is to provide a drainage system which will be easy to install and of low cost. These and 15 various other important objects and advantages of the invention will more readily become apparent to the reader after considering the following specification.

In the drawings:
20 Figure 1 represents a horizontal sectional view through a portion of the footing for a building showing the ditches layed off and filled with suitable coarse granular material through which water may easily seep.

25 Figure 2 represents a fragmentary vertical sectional view substantially on line 2-2 of Figure 1.

Referring to the drawings, wherein like numerals designate like parts, it can be seen 30 in Figure 2, that the numeral 5 represents the footing or foundation for the wall 6, this being all of the building disclosed in the drawings.

In carrying out the present system, a vertical bore 8 is made to terminate at a level 35 beneath the footing 5 and at spaced intervals outside of the confining area of the footing 5. Whether a ditch is dug straight downwardly or the work is consummated by tunnelling, is immaterial in providing the inwardly disposed ducts 9 which communicate the lower 40 ends of the bores 8 with the ditch 10.

This ditch 10 extends in close proximity to 45 the inner side of a building wall 6 and beneath the bottom level of the footing 5, as in the manner shown in Figure 2. A diagonally disposed ditch 11 connects one corner of the 50 ditch 10 with the diametrically opposite corner and in this last mentioned corner a drain

opening 12 is provided for communicating the ditch 10 with a drain pipe 13.

The ditches 10 and 11, and the ducts 9 are filled with some suitable coarse granular material such as crushed rock or gravel and as 55 shown in Figure 2, the bores 8 are filled to the level 14 with this material, and from there upwardly with earth.

The concrete or cement floor or covering 15 is then laid over the entire area within the confines of the footing 5. It will now be seen that any water percolating through the ground beyond the side walls of the building will eventually form fissures leading to the ducts 9 and when water has gained this point, 60 the same will readily sift through the granular material and ultimately pass into the drain pipe 13.

Thus the walls and flooring 15 will be maintained constantly dry by the novel system of 65 drainage.

Obviously certain variances of the system may be resorted to to accommodate various shaped structures without departing from 70 the spirit and scope of the invention as claimed hereinafter.

Having thus described the invention, what 75 is claimed as new is:

The combination with a building including foundation walls and a bottom floor, of 80 drainage means for the building comprising ditches arranged below the walls and floor and within the confines of the wall and following the outline thereof, a diagonal ditch connecting the corners of the first ditch together at opposite points, a drain pipe connected with the first ditch, and lateral ditches 85 connected with the first ditch and extending below and beyond the foundation walls.

In testimony whereof I affix my signature. 90
SAMUEL A. HARTMANN.
